UNITED STATES PATENT OFFICE.

WILLIAM J. COWAN, OF KANSAS CITY, KANSAS.

BURGLAR-GUARD SYSTEM.

Application filed July 25, 1922. Serial No. 577,431.

To all whom it may concern:

Be it known that I, WILLIAM J. COWAN, a citizen of the United States, residing at Kansas City, in the county of Wyandotte and State of Kansas, have invented certain new and useful Improvements in Burglar-Guard Systems, of which the following is a specification.

My invention relates to burglar guards for the protection of banks, post-offices, and other places in which money and other valuables are kept.

In carrying out the invention for the protection of a bank, for instance, the area enclosing the vault, the paying and receiving tellers and other clerks and officials is protected by a bullet proof wall in which the windows, through which business is transacted with the public, are equipped with

bullet proof shutters which can be quickly closed on the approach of an armed burglar, or burglars, and thus coat with said bullet proof wall in presenting a solid front for the protection of those within the enclosed area.

An electrical system is also employed and equipped with switches located at desirable points such as desks, on the floor, overhead etc., where they can be instantly reached and on the closing of any one of which circuits

will be established to automatically close the bullet proof shutters, sound local and distant alarms, lock the bullet proof door leading into the protected area and also the front door leading into the bank, so that the burglar, or burglars, may be entrapped in the room outside of the protected area and held until the arrival of the police.

Other features will hereinafter appear, and in order that the invention may be fully understood, reference will now be had to the accompanying drawings, in which:

Fig. 1 is a sectional plan view of a bank equipped with the invention.

Fig. 2 is an elevation of the bullet proof wall.

Fig. 3 is an enlarged detail of the shutters associated with the bullet proof wall, and the mechanism for controlling said shutters.

Fig. 4 is a vertical section on line IV—IV of Fig. 3.

Fig. 5 is a diagram of a control board for controlling the flow of current from the mains to the circuits embodied in the invention.

Fig. 6 is a broken detail of a door partly

in section, one of which is employed in connection with the bullet proof wall, and the other for controlling the ingress and egress to the street.

Fig. 7 is a detail of a contact and support associated with the doors.

Fig. 8 is a diagram of the circuits.

Referring now more particularly to the parts disclosed by Figs. 1 and 2, A designates a room to which ingress and egress is had through a front door B.

2 designates a bullet proof wall enclosing an area C in the room A and in which the clerical and official force of the bank, or other institution, is enclosed, said area containing among other features desks D, E and F. The enclosed area C also protects the entrance to the vault G in which the money and other valuables are kept.

Entrance is had to the area C through a bullet proof door 4 associated with the bullet proof wall 2, which latter has any desired number of window openings 6 through which the paying and receiving tellers, etc., transact business with the public. The window openings 6 have the usual protective grills 8, and in addition are protected by bullet proof shutters 10.

The shutters 10, Figs. 3 and 4, are arranged in pairs on the inside of the bullet proof wall 2. The upper ends of each pair operate in a guide 12 fixed to the inside of the bullet proof wall 2, while their lower ends are mounted upon antifriction rollers 14 which traverse stationary rail sections 16 fixed to the inside of the bullet proof wall 2.

The stationary rail sections 16 are spaced apart to admit a vertically movable rail section 18, which, when in the raised position disclosed by Fig. 3, abuts the shutters 10 and holds the same in open position. The stationary rail sections 16 are notched as indicated at 20 to receive lugs 22 at the ends of the movable rail section 18 when the same moves downwardly, so that the upper surface of said rail section 18 will be on a level with the upper surface of the rail sections 16 to permit the shutters 10 to move together as indicated by arrows a, a, Fig. 3, and close their respective window opening 6. The movable rail section 18 is normally held in raised position by an armature 24, which is forced beneath said rail section 18 when the same is manually raised to the position shown by Fig. 3, by a spring 26. An elec-

agnet 28 is provided, which when excited, attracts its armature 24 and withdraws the same from beneath the rail section 18, so the latter may drop to the level of the sections 16, as above stated.

hen the rail section 18 drops from beneath the shutters, the same are immediately held by mechanical means comprising bell-cranks 32 fulcrumed at 34, counterweights 36 adjustably secured upon said bell-cranks by suitable means such as set screws 38, connecting bars 40 pivoted at their ends to the respective shutters 10 and having pinslot connections 41 with the bell-cranks

ach door 4 and B is equipped with a lock 42 of any suitable design, Fig. In the present instance I have shown lock consisting of a case 44, a bolt 46 adapted to be retracted by a suitable key, a spring 48 for shooting the bolt into its proper 49, a lug 50 fixed to said bolt 46, an armature 52 for engaging said lug 50 to hold the bolt 46 in retracted position against the action of the spring 48, and an electromagnet 54, which when excited lifts the armature 52 out of the path of the lug 50, so that the spring 48 may shoot the bolt

The poles of the electromagnet 54 are connected by circuit wires 56 and 58 to contacts 66 and 68, respectively. The contacts 60 and 62 are mounted on a tubular bracket fixed to the upper portion of the door 1 through which the wires 56 and 58 extend. When the door is closed the contacts 60 and 62 engage contacts 66 and 68 connected to circuit wires 70 and 72, respectively. The contacts 60 and 62 are carried on a bracket 74 secured to the top of the door casing 76 or the burglar proof wall as the case may be.

The current for energizing the electrical apparatus is received over mains 78 and 80, the flow of current from said mains being controlled by electrical appliances mounted on a control board 82, Fig. 5. Said appliances consist, preferably, of a double pole single throw switch 84, the poles of which are connected by wires 86 and 88 to the mains 78 and 80, respectively; fuses 90 and 92 connected to opposite terminals of the switch 84 by wires 94 and 96; bus bars 98 and 100 connected to the fuses 90 and 92 by wires 102 and 104, respectively; bus bars 6 and 108 in contact with the bus bars 98 and 100, respectively; a transformer 110 having a primary coil 112 connected to the bus bars 106 and 108 by wires 114 and 116, respectively; a pair of oppositely disposed bus bars 118 and 120, the former of which is connected to the bus bar 100 and the latter to a bus bar 122; circuit wires 124 and 126 connected to the bus bars 98 and 122, respectively; a switch 128 to connect the bus bars 118 and 120; a relay 130 which,

when excited, closes the switch 128 through the intermediacy of an armature 132 and an insulated connecting rod 134; and a pilot lamp 136 in a circuit consisting of conductors 138 and 140 connected to the secondary 70 coil 142 of the transformer 110.

Referring now more particularly to the diagram Fig. 8, it will be seen that the circuit consisting of the wires 124 and 126 is connected in parallel to branch circuits 144, 75 146, 148, 150, 70-72, 70^a and 72^a and 154. The circuit 144 embodies an audible signal such as a bell 156 which may be located at a police station or other distant point. The branch circuits 146 to 150, inclusive, are 80 connected to the electromagnets 28 arranged at the windows 6. The branch circuit embodying the wires 70 and 72, the contacts 60, 62, 66 and 68, and the wires 56 and 58, is connected to the electromagnet 54 enclosed in the lock case 44. The branch circuit embodying the wires 70^a and 72^a is 85 also equipped with an electromagnet 54. The branch circuit 154 is connected to an audible signal, preferably, in the form of a gong 90 158 which may be located at the outside of the building to arouse the public to the fact that an attempted burglary is taking place. The branch circuits may be increased or reduced in number according to the number 95 of windows in the bullet proof wall 2 and the number of alarms it is desired to employ, it being understood that such alarms may be located at all desired points.

The circuit embodying the wires 138 and 140 is in series with a plurality of branch circuits 160, 162, 164, 168, 170 and 172, adapted to be closed by manually controlled switches, preferably, in the form of push buttons 174, 176, 178, 180, 182, and 184, respectively. 100 Said push buttons are located at all desirable points within the room, A, and within the protected area C adjacent to the desks, the windows, the door, and within the vault 110 G; they being, preferably, disposed in such manner that they may be operated without attracting the attention of a burglar.

Assuming that the doors 4 and B are closed but not locked and that the shutters 10 are in open position, the operation is substantially as follows: On the closing of any one of the push buttons, such for instance as the push button 184, the circuit through the wires 138 and 140 is closed. This energizes the electromagnet 130 which closes the switch 128. Current then flows from the main 78, through wires 86, one side of switch 84, wire 94, fuse 90, wire 102, bus bar 98, wire 124, and branch circuits 144, 146, 148, 150, 70 and 72, 56 and 58, circuits 70^a and 72^a, 56^a and 58^a, and circuit 154, returning to the main 80 through wire 126, bus bar 122, bus bar 120, switch 128, bus bar 118, bus bar 100, wire 104, fuse 92, wire 96, the opposite 120 side of the switch 84, and wire 88. Closing 130

of the circuits 148, 146 and 150 energizes their respective electromagnets 128 which withdraw the associate armatures 24 from beneath the movable rails 18, which being 5 sufficiently weighted drop to the level of the rails 16 and permit the weights 36 and the intervening mechanism to close the shutters 10. The closing of the branch circuits embodying the electromagnets 54 energizes said 10 electromagnets and causes them to raise the armatures 52 from the path of the lugs 50 and permit the springs 48 to shoot the bolts 46 and thus lock the doors 4 and B, so that a burglar cannot enter the protected area C, 15 or escape through the door B. On releasing of the push button 184 the shutters 10 remain closed and the doors 4 and B remain locked until manually restored to normal position. The mains 78 and 80 may carry 20 either a direct or an alternating current, but in the event that the former is used a bank of resistance will be substituted for the transformer 110 which is employed for reducing the voltage in the circuit wires 138 25 and 140 below that in the mains 78 and 80. All of the wires may be either concealed or arranged in armored conduits in order to be inaccessible to a burglar trapped in the room A. Police officers responding to the 30 alarm will be provided with keys for unlocking the front door B, so that those persons within the protected area C need not expose themselves for that purpose.

From the foregoing description it will be understood that I have provided a burglar guard embodying the features above pointed out, and while I have shown and described the preferred construction, combination and arrangement of parts, I reserve the right 40 to make such changes as properly fall within the spirit and scope of the claims.

Having thus described my invention, what I claim and desire to secure by Letters Patent, is:

45 1. In combination, a wall having an opening therein, a pair of oppositely disposed members for closing said opening, rail sections spaced apart and upon which said members are arranged to travel, a movable rail section intermediate said spaced rail sections and adapted to move to the level of the latter to form a continuous track upon which the members may move to closed position, electrically controlled means for normally holding said movable rail section in the path of the open members, and means 50 for closing the shutters when the movable section is released by said electrically controlled means and moves to the level of the spaced rail sections.

60 2. In combination, a wall having a window opening therein, a pair of oppositely disposed shutters for closing said opening, rail sections spaced apart and upon which said shutters are arranged to travel, a mov-

able rail section intermediate said spaced rail sections and adapted to move to the level of the latter to form a continuous track upon which the shutters may move to closed position, a magnetically controlled latch for 70 normally holding said movable rail section in the path of the open shutters, and means for closing the shutters when the movable section is released by said magnetically controlled means and moves to the level of the 75 spaced rail sections.

3. In combination, a wall having a window opening therein, a pair of oppositely disposed shutters for closing said opening, rail sections spaced apart and upon which 80 said shutters are arranged to travel, a movable rail section intermediate said spaced rail sections and adapted to move to the level of the latter to form a continuous track upon which the shutters may move to closed position, a latch for normally holding said movable rail section in the path of the open shutters, an electromagnet for retracting said latch so that the movable rail section may move to the level of the spaced rail sections 90 and permit the shutters to close, and a circuit for exciting said electromagnet.

4. In combination, a wall having an opening therein, a pair of oppositely disposed members for closing said opening, rail sections spaced apart and upon which said members are arranged to travel, a movable rail section intermediate said spaced rail sections and adapted to move to the level of the latter to form a continuous track upon 100 which the members may move to closed position, electrically controlled means for normally holding said movable rail section in the path of the open members, and weighted means for closing the members when the 105 movable section is released by said electrically controlled means and moves to the level of the spaced rail sections.

5. In combination, a wall having a window opening therein, a pair of oppositely disposed shutters for closing said opening, rail sections spaced apart and upon which said shutters are arranged to travel, a movable rail section intermediate said spaced rail sections and adapted to move to the level of the latter to form a continuous track upon which the shutters may move to closed position, electrically controlled means for normally holding said movable rail section in the path of the open shutters, levers 110 connected to said shutters, and means for causing said levers to close the shutters when the movable rail moves to the level of the spaced rails.

6. In combination, a wall having a window opening therein, a pair of oppositely disposed shutters for closing said opening, rail sections spaced apart and upon which said shutters are arranged to travel, a movable rail section intermediate said spaced 125 rails.

1 rail sections and adapted to move to the level of the latter to form a continuous track upon which the shutters may move to closed position, electrically controlled means for 5 normally holding said movable rail section in the path of the open shutters, levers connected to said shutters, and weights for causing said levers to close the shutters when

the movable rail moves to the level of the spaced rails.

In testimony whereof I affix my signature, in the presence of two witnesses.

WILLIAM J. COWAN.
